UNITED STATES PATENT OFFICE.

WILLIAM H. BELKNAP, OF NEW YORK, N. Y., ASSIGNOR OF ONE-FOURTH TO THOMAS B. LAW, OF BROOKLYN, NEW YORK.

STEAM-TURBINE ENGINE.

1,378,396.

Specification of Letters Patent. Patented May 17, 1921.

Application filed November 8, 1919. Serial No. 336,568.

To all whom it may concern:

Be it known that I, WILLIAM H. BELKNAP, a citizen of the United States, and residing at New York, in the county of New York and State of New York, have invented 5 certain new and useful Improvements in Steam-Turbine Engines, of which the following is a specification, such as will enable those skilled in the art to which it appertains to make and use the same.

This invention relates to turbine engines and particularly to engines of this class designed to be used for marine purposes and to be operated by steam under pressure; and 15 the object of the invention is to provide an engine of the class specified which will operate as a multiple expansion engine, which involves an improved cylinder, cylinder liner and rotor construction; a further object being to provide a valve construction 20 for engines of this class which in connection with the cylinder construction operates to produce a reversible engine; and with these and other objects in view the invention consists in a turbine engine of the 25 class specified which is simple in construction and operation and efficient in use.

The invention is fully disclosed in the following specification, of which the accompanying drawing forms a part, in which the 30 separate parts of my improvement are designated by suitable reference characters in each of the views, and in which:

Figure 1 is a plan and sectional view of 35 an engine made according to my invention and showing three cylinders;

Fig. 2 a side view looking in the direction of the arrow 2 of Fig. 1;

Fig. 3 an end view looking in the direction of the arrow 3 of Fig. 1 and with part 40 of the construction broken away and in section;

Fig. 4 a partial section on the line 4—4 of Fig. 1;

Fig. 5 a partial section on the line 5—5 45 of Fig. 1;

Fig. 6 a plan view of the cylinder liner shown in Fig. 3 detached and on an enlarged scale;

Fig. 7 a view looking in the direction of the arrow 7 of Fig. 6;

Fig. 8 a view similar to Figs. 6 and 7 but showing a bottom plan view of the cylinder liner shown in Fig. 3;

Fig. 9 a partial section on the line 9—9 55 of Fig. 6 on a reduced scale; and,

Fig. 10 a partial section on the line 10—10 60 of Fig. 3 and on an enlarged scale.

In the drawing I have shown at 11 a power or propeller shaft which passes 65 through three cylinders 12, 13 and 14 spaced longitudinally of said shaft, and mounted in the cylinders are cylinder liners 15, 16 and 17. Secured to the shaft 11 within the separate cylinders, or the liners thereof, 65

are rotors 18, 19 and 20, this construction being shown in detail in Figs. 3, 4 and 5. At one side of the cylinders 12 and 14 are mounted intake manifolds 21 and 22, and at the opposite sides of said cylinders 70 are exhaust pipes 23 and 24. The cylinder 13 is provided with an intake manifold 25 on the side of the engine to which the exhaust pipes 23 and 24 of the cylinders 12 and 14 are secured and on the opposite side 75 of the cylinder 13 is an exhaust pipe 26. The intake manifold 21 of the cylinder 12 is provided with a threaded extension 27 with which a steam supply pipe is adapted to be connected. The exhaust pipe 23 of 80 the cylinder 12 is connected with the intake manifold 25 of the cylinder 13 as shown at 28, while the exhaust pipe 26 of the cylinder 13 is connected with the intake manifold 22 of the cylinder 14, as shown at 29, while 85 the exhaust 24 of the cylinder 14 passes out into the open, or is connected with a suitable tank which is not shown.

Mounted in the intake manifolds 21, 25 and 22 are two-way valves 30, 31 and 32 90 respectively, which are adapted to control the passage of steam into the separate cylinders through intake ports or passages 33—34, 35—36 and 37—38 in the separate cylinders 12, 13 and 14 and said intake manifolds. 95 The steam passed into and through the separate cylinders, as hereinafter described, is discharged through exhaust ports or passages 39, 40 and 41, and these discharges are controlled by pivoted valve devices 42 mounted in the cylinder liners 15, 16 and 17.

The valves 30 and 32 are connected by an operating shaft 43 and the valve 31 which is at the opposite side of the engine is operated from the shaft 43 through a gear construction consisting of a large gear 44 rotatably mounted on an extension 45 at one side of the cylinder 13, and a gear 46 on

the shaft 43 and a corresponding gear 47 on the shaft 48 of the valve 31. From the foregoing it will be seen that by rotating the shaft 43 to open or close the valves 30 5 and 32, the shaft 48 of the valve 31 will be correspondingly rotated to open or close said valve, and while I have shown a specific means of accomplishing the desired result, it will be apparent that I am not necessarily limited to this means.

The cylinders 12, 13 and 14 are open at one side to permit of the connection of the cylinder liners with said cylinders and the placement of the rotors within said liners, and 15 the open ends of the cylinders are closed by end plates 49 held in place by screws or bolts 50. The cylinder liners 15 and 16 are both of the same general form and construction but are of slightly different dimensions, and in Figs. 6 to 9 inclusive, I have shown detail views of the cylinder liner 15, which consists of a ring or band of predetermined thickness. The outer face of this band is cut out or recessed as shown at 51 25 and 52 to form two independent intake passages at one side edge portion of the liner, and also recessed or cut out to form a single exhaust passage 53 at the opposite side thereof, and the exhaust passage 53 is 30 separated from the intake passages 51 and 52 by partition walls 54 and 55 respectively, as clearly shown in Figs. 6 and 8.

The intake passage 51 is provided with three nozzles 56 of varying transverse widths 35 due to the shape of the passage 51, while the intake passage 52 is provided with two nozzles 57 of different transverse width. The exhaust passage 53 is provided with two sets of ports divided by the valve 42, one of 40 these sets consisting of three ports 58 and the other of two ports 59, as clearly shown in Figs. 6 to 9 inclusive.

The above described construction also applies to the cylinder liner 16 shown in Fig. 45 4 of the drawing, except that the dimensions of the nozzles and ports 56 to 59 inclusive are slightly greater than those in the cylinder liner 15. The cylinder liner 17 is also of the same general form and construction as the 50 liners 15 and 16, except that the intake passages 51 and 52 are each provided with two nozzles 56 and 57 respectively, and the exhaust passage 53 of said liner is also provided with four ports 58-59, arranged in 55 pairs. The reason for the variation in construction of the liner 17 from the liners 15 and 16 is due to the fact that the nozzles and ports 56 to 59 inclusive in the liner 17 are of such dimensions as to permit of the 60 use of but two pairs of intake nozzles and two pairs of exhaust ports, and it is also believed that this number will be sufficient to accomplish the desired result.

The separate rotors 18, 19 and 20 are provided in the periphery or outer face thereof

with a plurality of approximately circular apertures 60 which open outwardly through the periphery of said rotors to form a plurality of pockets divided by intermediate webs 61, and these pockets increase in capacity 70 from the rotor 18 to the rotor 20 as will be seen on a consideration of Figs. 3, 4 and 5 of the drawing. It will also be noted that the intake passages 33-34, 35-36, and 37-38 increase in dimensions or capacity, 75 as do also the exhaust passages 39, 40 and 41, and the nozzles and ports 56 to 59 inclusive, in the cylinder liners 15, 16 and 17.

From the foregoing description the operation of my improved engine will be readily understood when taken in connection with the accompanying drawing and the following statement. The valves 30, 31 and 32 are shown in their open position in Figs. 3, 4 and 5 so that steam may pass through the intake ports or passages 33, 35 and 37 into the intake passages 51 of the separate cylinder liners 15, 16 and 17 through the nozzles 56 of said passages into the pockets 60 of the rotors 18, 19 and 20 to rotate said rotors and 90 the shaft 11. It will be noted on a consideration of Figs. 3 and 6 to 9 inclusive that immediately after the steam in the passage 51 of the cylinder liners 15 has passed through the nozzles 56 into a predetermined number 95 of the pockets 60 of the rotor 18, the steam in said pockets will be discharged therefrom into the passage 53 of the cylinder liner 15 through the discharge ports 58, and this steam then passes out through the exhaust 100 39 into the intake manifold 25 thus through the cylinder and cylinder liner 13 and 16 and rotor 19 out through the exhaust 40 in the same manner as the passage of steam through the first named cylinder, except that 105 the steam is directed downwardly into the cylinder 13 instead of upwardly as in the cylinder 12 in order that the shaft 11 may be rotated in the same direction. The steam from the exhaust 20 is then passed into the 110 cylinder 14 and liner 17 and rotor 20 thereof, and out through the exhaust 40 in the same manner as the passage of the steam through the cylinder 12, except that the steam is discharged into the pocket 60 of the rotor 20 115 through two intake nozzles instead of three, and is exhausted through two exhaust ports. While I have stated that the steam passed into the pocket or pockets 60 of the various rotors is immediately discharged therefrom, 120 it is apparent that this discharge takes place after the rotor has made a fraction of a revolution, or takes place between the separate intake nozzles 56 as is indicated in dotted lines in Figs. 3, 4 and 5. It will also be 125 apparent that the valve 42 will operate to close the communication between the separate portions of the exhaust passage 53 in the separate cylinder liners 15, 16 and 17 so that the exhausted steam from the sepa- 130

rate cylinders cannot pass into the pockets of the rotors through the exhaust ports 59 of said cylinder liners thus keeping the steam in constant and true circulation.

- 5 The above description relates to the forward driving of the engine. When it is desired to reverse the rotation of the shaft 11, and the rotors thereon, the valves 30, 31 and 32 are rotated by means of the shaft 43 and gears 44, 46 and 47 to place the intake ports or passages 34, 36 and 38 in communication with the ports of said valves so that the steam will pass into the intake passages 52 of the cylinder liners 15, 16 and 17 and 10 into the pockets 60 of the separate rotors through the nozzles 57, and this steam is discharged from the separate exhaust passages 53 of said cylinder liners through the ports 59 thereof, and in this operation the valves 42 will operate to close the communication between the ports 58 and 59 of the passages 53 thus keeping the steam in a constant flow to propel the shaft 11 in a reversed direction. In Fig. 1 I have shown 15 sleeves 62 and 63 mounted on the shaft 11 outwardly of the cylinders 12 and 14 which serve to take up the thrust and relieve the strain of the rotors on the walls of the cylinder liners and cover plates 49.
- 20 It will be apparent that while I have shown certain details of construction for carrying my invention into effect, that I am not necessarily limited to these details, and various changes in and modifications of the 25 construction herein shown and described may be made, within the scope of the appended claims, without departing from the spirit of my invention or sacrificing its advantages.
- 30 Having fully described my invention, what I claim as new and desire to secure by Letters Patent, is:—

1. An engine of the class described comprising a cylinder, a shaft passing through 35 said cylinder, a cylinder liner for said cylinder, a rotor mounted in said cylinder liner and secured to said shaft, a plurality of intake passages in said cylinder liner, an exhaust passage in said cylinder liner, said

intake and exhaust passages being provided 50 with ports, a plurality of independent pockets in said rotor and adapted to communicate with said ports, independent intake ports in said cylinder and communicating with the intake passages of said cylinder 55 liner, a valve device for controlling said intake ports, and an exhaust port in said cylinder and in communication with the exhaust passage of said cylinder liner.

2. An engine of the class described comprising a cylinder, a shaft passing through said cylinder, a cylinder liner for said cylinder, a rotor mounted in said cylinder liner and secured to said shaft, a plurality of independent intake passages in said cylinder 60 liner, an exhaust passage in said cylinder liner, said intake and exhaust passages being provided with ports, pockets in said rotor and adapted to communicate with said ports, independent intake ports communicating 65 with the intake passages of said cylinder liner, a valve device for controlling said intake ports, an exhaust port communicating with the exhaust passage of said cylinder liner, and a valve device for sub-dividing 70 the exhaust passage of said cylinder.

3. A turbine engine of the class described comprising a cylinder, a rotor mounted in said cylinder and the periphery of which is provided with a plurality of independent 80 pockets, means for supplying steam to the cylinder, an annular cylinder liner independent of and mounted in said cylinder and provided with ports for discharging steam into the pockets of said rotor at a plurality 85 of points about the periphery thereof, and other ports in said liner in juxtaposition to and at one side of said first named ports for exhausting the steam from said pockets, said parts being divided by a partition wall. 90

In testimony that I claim the foregoing as my invention I have signed my name in presence of the subscribing witnesses this 6th day of November, 1919.

WILLIAM H. BELKNAP.
